(57) **CLAIM**

The ornamental design for a cremation urn, as shown and described.

DESCRIPTION

FIG. 1 is a top front perspective view of one embodiment of our new, original and ornamental design for a cremation urn. FIG. 2 is a front view thereof, the back view, left side view, and right side view thereof being identical thereto.

FIG. 3 is a top view thereof; and,

FIG. 4 is a bottom view thereof.

The broken line depict environment that forms no part of the claimed design. The unshown portions of the article form no part of the claimed design.
